TYPE-WRITING MACHINE.

1,199,228

specification of Letters Patent. Patented Sept. 26, 1916.

Application filed October 11, 1913. Serial No. 734,597.

To all whom it may concern:

Be it known that I, Nils H. Anderson, a citizen of the United States, residing at Middletown, in the county of Middlesex and 5 State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and with regard to certain more specific features thereof, to the mechanism 15 known to those familiar with the practical operation of a typewriting machine, as an alining scale or card holder.

One of the objects of the present invention is to provide a simple and practical device 20 of the above character which will be efficient in operation.

Another object is to provide an improved form of alining scale indicating also at all 25 times the exact printing point.

Another object is to provide a device of the first above-mentioned character capable 30 of ready manipulation and adjustment in order that the device may be operated more satisfactorily upon cards or paper of varying thickness.

A further object is to provide a construction having few parts compactly arranged whereby the same will be cheap to manufacture, easy to assemble and not likely to get 35 out of order.

Other objects will be in part obvious and in part pointed out hereinafter.

The invention accordingly consists in the features of construction, combinations of 40 elements and arrangement of parts which will be exemplified in the construction hereinafter set forth, and the scope of the application of which will be indicated in the following claims.

In the accompanying drawing, in which is illustrated one of the various possible embodiments of the several features of the invention, Figure 1 is a plan view showing such parts of a typewriting machine as are 50 necessary to illustrate the application of

the present invention thereto. Fig. 2 is a side elevation of the parts shown in Fig. 1; Fig. 3 is a front elevation with certain parts being shown in section, or broken away, for the sake of clearness.

55

Similar reference characters refer to similar parts throughout the different views of the drawing.

While the present invention will be described hereinafter with relation to its application to a noiseless typewriting machine in which the type carriers are radially disposed with respect to a common printing point and coact with the platen by pressure in contradistinction to impact, it is, of course, to be understood that this mechanism may be applied to other forms of typewriting machines as well without departing from the intended scope of the invention. It is believed to be unnecessary to show or 60 describe any form of type action and associated parts, as the functions are well known to those familiar with the art.

Referring now in detail to the accompanying drawing and more particularly to 65 Figs. 1 and 2, a platen roller 1 is carried by a carriage 2 traveling along a horizontally disposed shift rail 3 in the usual well-known manner. Between the end walls 4 of the platen carriage and positioned adjacent to 70 the platen roller is a flat sheet-metal platen 5 adapted to take up the thrust or pressure of the type carriers one of which is indicated at 9. The paper is adapted to be fed downward about the platen roller from a 75 paper table 6, and upward over the flat platen extending across the front of the platen roller.

Among the several means used for holding the paper in engagement with the platen, there is provided what will be termed hereinafter for convenience, an "alining scale" 7 of flat sheet metal provided with laterally extending arms 8 at each side co-acting with a relatively large 80 surface of the flat platen 5, or having a total spread of perhaps half the length of the platen roller. This scale, which is also a printing point indicator, is provided, also, with downward extending arms 10 formed 85

85

90

95

100

integrally with the lateral arms and having rearward extending ears 11 at their lower ends, through slots in which pass adjusting screws 12 engaging tapped-out portions on 5 an auxiliary bracket 13 carried by a main bracket 14 secured in any desired manner to the shift rail 3 along which the carriage travels. It is to be noted that the arms 8 and 10 carrying the scale 7 are all of one 10 piece, but not necessarily so, it being easier and cheaper to make the parts in this manner. The auxiliary bracket 13 as shown more clearly in detail, Fig. 3, is mounted upon trunnions in the form of adjusting screws 15 passing through the sides of the main bracket 14 and provided with lock nuts 16 in order to maintain them in adjusted position. The screws passing through the ears 11 in the alining scale are adapted to permit an 15 independent vertical adjustment of the alining scale 7 in order that it may properly coact with the lower edge of the printing line. The adjusting screws 15 supporting the auxiliary bracket are particularly adapted to 20 permit lateral adjustment in order that the indices upon the alining scale 7 may properly coact with the central portion of each 25 printed character, the vertical and lateral adjustments being capable of being made independently of each other. It is, of course, to be understood that after these adjustments are once made, further adjustments 30 will probably be unnecessary.

The alining scale 7 is spring pressed 35 against the platen, or paper, if in place, by a flat spring 17, secured by means of a set screw 18 to the rear of the main bracket 14, which bears against the upper edge of the auxiliary bracket 13, as shown in Fig. 2. 40 The right and left hand ends of the alining scale proper are connected across the open center exposing the printing point by an upwardly extending arched portion 20 which is also curved backward above the 45 printing point, as shown in Fig. 2, thereby to deflect the paper and hold the same in contact with the platen roller.

The shape of the central opening in the upward extending portion 20 through which 50 the type pass when making the printed impression, is of importance, since it guides the feeding of the paper, and due to the curved arch particularly prevents the corners of the paper from catching in the opening if the corner happens to be just above the inner edge of the laterally extending portion 8 of the scale when the carriage is moved to right or left, or if the paper is fed into the machine in such position that the 55 corner thereof, would tend to enter or pass out of the opening. The inner ends of the laterally extending arms 8 of the alining scale are turned slightly forward away from the platen as shown at 21 in Fig. 1 to pre-

vent catching of the paper during the letter-space movement of the carriage. The upper end of the arched connecting portion 20 is provided with a V-shaped notch, 22, the space between the two upper points of which represents the writing space or width 65 of one letter and the bottom of the point of the V being directly above the center of the printing point. In a machine using the pica type, for example, the printing space would be .10", so that the opening of the V 70 would be of that amount in such a machine. The two upper points of the V are also a certain number of lines above the normal writing line so that when inserting a character the space in which the same is to be inserted, is brought into alinement with the points of the V and then the paper is fed backward to the printing line, the line-space mechanism of the platen roller controlling 75 accurately the position thereof. In order that the writing line may be exposed as much as possible, the scale is provided with openings 24 at each side of the printing point which assist in making the line being written, as near visible at all times as possible. 80

In a double-shift machine using straight thrust type carriers in which the type are positioned one above the other with their printing surfaces in substantially the same 95 plane, there is, when writing a large number of sheets, a tendency for the upper and lower type to overscore or underscore the printing line. The present alining scale has an important relation with the paper-feeding qualities of a machine of this character, as it holds the paper more closely against the platen roller and back of the plane of the flat platen thereby preventing buckling or swelling of the paper at the printing 100 point, thus eliminating the tendency to overscore and underscore during the printing operation. The overscoring is prevented by the rearward curved arched portion 20, while the underscoring is prevented by 105 means of a plurality of flexible spring arms or fingers 25 riveted to the arms 10 supporting the alining scale. These arms 25 extend backward against the platen roller, as clearly shown in Fig. 2 and are made of 110 relatively light resilient material to hold the paper against the platen roller just below the flat platen 5, thereby materially assisting in the elimination of the tendency to underscore. 115

The present device may serve either as an alining scale or a card holder, but when intended to hold cards it is preferred to introduce additional spring tension intermediate the scale and final point of resistance. 125 This mechanism comprises a resilient arm 26 extending downward from the auxiliary bracket and is provided with a forward ex-

tending portion 27, the forward end of which forms a hook 28 to engage a pull wire or connecting link 30 extending toward the front of the machine. The rear end of the connecting link is suitably formed to engage the hook as shown, while its forward end is provided with a flattened, or reduced portion 31 for clearance of the type action pull wires and other parts not shown. The forward end of the link is provided with an adjusting nut 32 and a lock nut 33 threaded thereon.

Extending downward from the top plate of the machine is a supporting post 34 carrying at its lower end a bracket 35. This bracket is provided with a horizontally disposed portion 36 at its lower end carrying the pivot screw 37 upon which a lever 38 is mounted. The rear end of this lever has an upward turned portion 40 forked for engagement with the forward end of the connecting link 30 directly back of the adjusting nut. The bracket also has a rearward extending portion 41 provided with a slotted upturned end to guide the forward end of the connecting link as shown. The forward end of the lever 38 passes through the front plate 42 of the machine and is provided with a handle 43 appearing just above the keyboard and below an indicating dial 44 on the front panel marked "P" and "C", denoting the use of the mechanism for either paper or cards. The position of the lever is controlled by means of a flat, sheet-metal spring 45 secured to the bracket 36 and engaging one or the other of two notches 46 in the horizontal portion of the lever adjacent its pivot point 37.

The operation of this mechanism is substantially as follows: When the parts are in the position shown in Figs. 1 and 2, the alining scale 7 is held against the paper on the platen with a relatively light pressure, the connection of the link with the operating lever permitting the parts to accommodate themselves to any position, depending upon the amount of the paper which is introduced into the machine. Under these conditions there is only a light spring tension from the spring 17 on the alining scale and on the paper, it being sufficient to hold the paper when feeding, but preferably not strong enough to hold an index card against the platen with the desired pressure and result. When it is desired to feed cards in the machine, the handle 43 of the lever 38 is moved from the position shown in Fig. 1 to a point adjacent the letter "C", at which time the forked end 40 passes behind the adjusting nut 32 and acts to prevent a rearward movement of the connection 30 when the cards are introduced into the machine. This operation is practically the same as introducing additional spring tension into the

alining scale due to the flexibility of the downward extending arm 26. When feeding cards the shape of the opening in the alining scale is of even greater value than when feeding paper, since on account of the short length of the card, the corners very frequently pass into the central opening, as it is usually desired to write very near the edge or margin of the card. The shape of the alining scale, and particularly of the opening in the central part thereof, is such that the corners of the cards will pass behind the alining scale without interference or catching in the central opening.

It is thus seen that this invention provides a combined alining scale and card-holding device that may be readily changed from one to the other to satisfy the paper-feeding conditions of both. The means for changing the device from one to another is positioned adjacent the keyboard in an accessible position for the operator. The invention is therefore believed to comprise a simple and practical device, accomplishing, among others, all the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, in combination, a platen, a member adapted to be pressed toward the platen, a member adapted to be manually operated and connections between the first and second said members whereby said first member may be pressed toward the platen, and means adapted automatically to lock said second member in different positions.

2. In a typewriting machine, in combination, a platen, a member adapted to be pressed toward the platen, spring means normally urging said member toward the platen, a member adapted to be manually operated and connections between the first and second members whereby said first member may be pressed toward the platen, and means adapted automatically to lock said second member in different positions.

3. In a typewriting machine, in combination, a platen, a member comprising an alining scale adapted to be pressed toward the platen, a member adapted to be manually operated and connections between the first and second members whereby said first member may be pressed toward the platen,

and means adapted automatically to lock said second member in different positions.

4. In a typewriting machine, in combination, a platen, a member comprising an alining scale, adapted to be pressed toward the platen, spring means normally urging said member toward the platen, a member adapted to be manually operated and connections between the first and second said members whereby said first member may be pressed toward the platen, and means adapted automatically to lock said second member in different positions.

5. In a typewriting machine, in combination, a platen, a member comprising an alining scale having a notch which bears a predetermined transverse and longitudinal position with respect to the printing point, adapted to be pressed toward the platen, a member adapted to be manually operated and connections between the first and second members whereby said first member may be pressed toward the platen, and means adapted automatically to lock said second member in different positions.

6. In a typewriting machine, in combination, a platen, a member adapted to be pressed toward the platen and having a rearwardly extending portion above the printing line, a member adapted to be manually operated and connections between the first and second said members whereby said first member may be pressed toward the platen, and means adapted automatically to lock said second member in different positions.

7. In a typewriting machine, in combination, a platen, a member adapted to be pressed toward the platen, carrying means adapted to bear below the printing line on the work sheet, a member adapted to be manually operated and connections between the first and second said members whereby said first member may be pressed toward the platen, and means adapted automatically to lock said second member in different positions.

8. In a typewriting machine, in combination, a platen, a member comprising an alining scale adapted to be pressed toward the platen, a spring normally pressing said member toward the platen, and supplemental spring means adapted to be rendered effective at the will of the operator whereby additional pressure of said member toward the platen is obtained.

9. In a typewriting machine, in combination, a platen, a member comprising an alining scale adapted to be pressed toward the platen, a spring normally pressing said member toward the platen, supplemental spring means adapted to be rendered effective at the will of the operator whereby additional pressure of said member toward

the platen is obtained, and locking means for automatically securing said last means in effective position.

10. In a typewriting machine, in combination, a platen roller, and a member adapted to be pressed toward said platen comprising an alining edge and index on either side of the printing point, said member carrying means below the line of printing for urging the paper toward said platen roller.

11. In a typewriting machine, in combination, a platen roller, and a member adapted to be pressed toward said platen comprising an alining edge and index on either side of the printing point and an arch extending around the printing point, said member carrying means below the line of printing for urging the paper toward said platen roller.

12. In a typewriting machine, in combination, a platen roller, a member adapted to be pressed toward said platen comprising an alining edge and index on either side of the printing point, said member carrying means below the line of printing for urging the paper toward said platen roller, and spring means normally pressing said member toward the platen.

13. In a typewriting machine, in combination, a platen roller, a member adapted to be pressed toward said platen comprising an alining edge and index on either side of the printing point and an arch extending around the printing point, said member carrying means below the line of printing for urging the paper toward said platen roller, and spring means normally pressing said member toward the platen.

14. In a typewriting machine, in combination, a platen roller, a member adapted to be pressed toward said platen comprising an alining edge and index on either side of the printing point, and spring means adapted to be rendered effective or ineffective at the will of the operator whereby said member is urged toward the platen.

15. In a typewriting machine, in combination, a platen roller, a member adapted to be pressed toward said platen comprising an alining edge and index on either side of the printing point and an arch extending around the printing point, said member carrying means below the line of printing for urging the paper toward said platen roller, and spring means adapted to be rendered effective or ineffective at the will of the operator whereby said member is urged toward the platen.

16. In a typewriting machine, in combination, a platen roller, a member adapted to be pressed toward said platen comprising an alining edge and index on either side of the printing point, spring means normally

pressing said member toward said platen roller, and supplemental spring means adapted to be rendered effective or ineffective at the will of the operator whereby said member is urged toward the platen.

17. In a typewriting machine, in combination, a platen roller, a member adapted to be pressed toward said platen comprising an alining edge and index on either side of the printing point and an arch extending around the printing point, said member carrying means below the line of printing for urging the paper toward said platen roller, spring means normally pressing said member toward the platen, and supplemental spring means adapted to be rendered effective or ineffective at the will of the operator whereby said member is urged toward the platen.

18. In a typewriting machine, in combination, a platen, and an alining scale adapted to coöperate therewith having lateral extending arms forming a straight edge at each side of the printing point and a member integrally connected with both of said arms arched over the printing point, said member having an index directly above the printing point and a predetermined number of line spaces therefrom.

19. In a typewriting machine, in combination, a platen, an alining scale adapted to coact therewith having a downwardly extending spring arm, means operable from the keyboard and connected with said spring arm for locking the same against movement, said means including a pivotally mounted lever and a connecting rod between said lever and spring arm adapted to be positively connected at their adjacent ends.

20. In a typewriting machine, in combination, a platen, an alining scale adapted to coact therewith, and means adapted to be held against movement to increase the pressure of said scale on the platen whereby it is changed from a paper holder to a card holder at will, said means including a link connected with the scale and a lever adjacent the keyboard of the machine adapted to be connected and disconnected with the link at will.

21. In a typewriting machine, in combination, a platen, an alining scale adapted to coact therewith, and means adapted to be held against movement to increase the pressure of said scale on the platen whereby it is changed from a paper holder to a card holder at will, said means including a link connected with the scale carrying a nut at one end thereof and a forked lever operable from the keyboard adapted to engage said nut to connect the lever and link.

22. In a typewriting machine, in combination, a platen, an alining scale adapted to

coact therewith, means adapted to be held against movement to increase the pressure of said scale on the platen whereby it is changed from a paper holder to a card holder at will, said means including a link connected with the scale carrying a nut at one end thereof, a forked lever operable from the keyboard adapted to engage said nut to connect the lever and link, and means adjacent the keyboard for indicating the position of said connection.

23. In a typewriting machine, in combination, a platen, an alining scale adapted to coact therewith, an arm connected with said scale, a link connected with said arm, and means adapted to be connected and disconnected with said link at will for varying the operative effective pressure with which said scale is adapted to bear against the paper.

24. In a typewriting machine, in combination, a platen, an alining scale adapted to coact therewith, an arm connected with said scale, a link connected with said arm, means adapted to be connected and disconnected with said link at will for varying the operative effective pressure with which said scale is adapted to bear against the paper, and means adapted to indicate the condition of said connection.

25. In a typewriting machine, in combination, a platen, an alining scale adapted to coact therewith, an arm connected with said scale, a link connected with said arm, means adapted to be connected and disconnected with said link at will for varying the operative effective pressure with which said scale is adapted to bear against the paper, and means adjacent the keyboard of the machine adapted to indicate the degree of pressure with which said scale is adapted to coact with the paper.

26. In a typewriting machine, in combination, a pivotally movable alining scale, means whereby said scale may be adjusted vertically, and independent means for adjusting said scale laterally.

27. In a typewriting machine, in combination, a pivotally movable alining scale, and independent means whereby said scale may be adjusted in two directions at substantially right angles to each other.

28. In a typewriting machine, in combination, a pivotally movable alining scale, a platen with which said scale is adapted to coact, said scale being formed of sheet metal and having a central opening through which the type are adapted to pass to the printing point, means whereby said scale may be adjusted vertically, and independent means whereby said scale may be adjusted in a direction at substantially right angles thereto.

29. In a typewriting machine, in combination, a platen, an alining scale therefor having a pivotal movement therebelow, and

means operable from adjacent the keyboard of the machine for urging said scale against said platen.

30. In a typewriting machine, in combination, a platen, and a pivotally mounted alining scale therefor having lateral wings and a symmetrically arched portion connecting the same above the printing line, said portion being provided with a V-shaped

notch centered with respect to the printing point.

In testimony whereof I affix my signature, in the presence of two witnesses.
